UNITED STATES PATENT OFFICE.

JOHN NEWBERRY REYNOLDS, OF GREENWICH, CONNECTICUT. ASSIGNOR TO WESTERN ELECTRIC COMPANY, OF NEW YORK, N. Y., A CORPORATION OF ILLINOIS.

AUTOMATIC SELECTOR-SWITCH.

1,091,765.

Specification of Letters Patent. Patented Mar. 31, 1914.

Application filed July 8, 1911, Serial No. 637,434. Renewed May 16, 1913. Serial No. 768,157.

To all whom it may concern:

Be it known that I, JOHN NEWBERRY REYNOLDS, citizen of the United States, residing at Greenwich, in the county of Fairfield and 5 State of Connecticut, have invented a certain new and useful Improvement in Automatic Selector-Switches, of which the following is a full, clear, concise, and exact description.

10 This invention relates to automatic switches of the panel type, for automatically effecting the interconnection of telephone lines, and is adapted for use in either automatic or semi-automatic telephone exchange 15 systems. In this type of switch the terminals are assembled in vertical rows in a large flat-faced bank or panel over which brushes are carried vertically in a straight line to the desired terminal. These terminals may be 20 multiplied horizontally across the board to be accessible to as many individual selector mechanisms as are necessary to take care of the maximum simultaneous number of calls. The rows of terminals may be divided horizontally into banks or sections, a brush being provided in each section for each row. The brushes associated with the sections of the same row are carried upon a common support. Thus any terminal may be reached 25 by some brush in a relatively short movement of the support. Means are provided for determining which of the brushes on the support shall be rendered operative, thus in effect selecting the group by selecting the 30 brush.

One of the objects of this invention is to provide an improved means for selecting the brush to be rendered active.

Another feature of the invention resides 40 in the elevating mechanism for the brushes. In the embodiment of the invention herein disclosed each of the sets of brushes serving the vertical rows of multiple terminals is arranged in operative relation to an actuating 45 device which is normally free of engagement with all the brushes but adapted to seize an individual brush or rather a set of brushes and move it along its row of terminals in its respective division of the panel to the exclusion of the others.

The mechanical selective means shown comprises an elevating rod common to the sets of brushes serving the sections into which the panel is divided, said rod being 55 adapted in one movement to seize the proper

brush and in another movement to elevate the same to the desired terminal in its division. This may be accomplished by providing the rod with pins, one for each brush, adapted when the rod is twisted to respectively engage fingers upon the brush carriers and elevate the same, the relation of the respective pins to their corresponding fingers being such that only one pin and its corresponding finger will be in alinement at the time the twisting action occurs. In the present embodiment this is accomplished by varying the height of the fingers of the respective brush carriers with respect to the resting positions of the pins in arithmetical progression from the bottom to the top carrier. The rod may be twisted by a lever actuated by a magnet. The selected brush may be raised by power applied to the lifting rod by a constantly rotating pulley to 75 which it is coupled, and may be restored by gravity.

The elevating mechanism for the brushes consists of a driving pulley located in operative relation to the elevating means, in the present instance a rod, and an idler pulley adapted to force the rod into engagement with the pulley to elevate the same. Preferably a pair of driving pulleys are provided both in operative relation to the brush rod, and each adapted to impart a different rate of travel to said rod. The idler pulleys may be carried by levers actuated by electromagnets.

Referring to the drawings—Figures 1, 2 and 3 should be viewed one below the other in the order named and show a side elevation of a part of an individual selector and a section of the corresponding part of the panel board before which it travels; Fig. 4 is a partial section on line 5—5 of Fig. 2, and Fig. 5 is a complete section on the same line. These views illustrate the successive positions of a brush-lifting pin and the corresponding finger during the seizure of a brush; Fig. 6 is a similar section and illustrates the relation of the pins to the fingers of the other brushes after the rod has been twisted and the selected brush seized; Fig. 7 is a section of the commutator on the line 7—7 of Fig. 2; Fig. 8 is a sectional view on the line 9—9 of Fig. 5, Fig. 9 is an end view of what is shown in Fig. 7 looking in the direction of the arrows; Fig. 10 is a section of the shift arm for the brush rod, on line

10—10 of Fig. 1; Fig. 11 is a perspective of the retaining pawl for the brush rod; Fig. 12 is a sectional view of the brush rod holding and release mechanism on line 12—12 of 5 Fig. 1; Fig. 13 is a perspective view of the means for preventing accidental elevation of the brushes; and Fig. 14 is a view of the finger by means of which the associated brush is elevated by the engaging pin of the lift 10 rod.

The selector shown is capable of serving five hundred lines divided into five horizontal banks of a hundred terminals each, multiplied so as to be accessible to brushes 15 traveling before each of its faces. In order, however, to avoid needless duplication of parts and to give a clearer idea of that part of the structure claimed herein, only portions of two successive banks of line terminals 20 66 are shown, it being understood that for each of the rows in the three omitted sections of terminals a brush carrier 28 with its brushes 29, 30, 31 and 32 is provided. Each individual selector mechanism may 25 comprise high and low speed elevating clutches 75, 76, shown in Fig. 3; a brush lifting rod 25, extending the entire length of the panel and passing between the elevating pulleys 51, 52 of the respective clutches; 30 five brush carriers 28, each with three brushes 29, 30, 31, 32, (30 and 31 being in effect one) adapted to contact with the fixed terminals 34, 35 and 36 in their movement, as shown in Fig. 5, when elevated by the rod 25, current-supplying members 29', 30', 32' for the 35 respective brushes 29, 30, 32, a shift magnet 45, a shift arm 42, a brush-rod retaining pawl 39 and brush-rod release magnet 46 shown in Fig. 1, and a commutator 57 which 40 serves to send back impulses as a brush is elevated, to govern its movement.

The brush rod 25 is provided with a pin 47 for each brush carrier 28. These pins normally rest on screws 77 in the base plates 45 67 of their respective sections and in the present embodiment are equidistant from each other upon the brush rod 25. Each of the brush carriers 28 has a finger 48 with which the corresponding pin only is adapted 50 to interlock. These fingers are arranged on the carriers so that in the normal positions of the carriers they are at successively increasing heights from the normal position of the pins 47 which rest, speaking broadly, 55 upon the floors 67 of the respective sections (see Fig. 2). The fingers 48 are in line with each other and out of the line of the upward travel of the pins 47, as shown in Fig. 6, but the brush rod 25 is free to twist on its own 60 axis so as to permit of the pins engaging and seizing their respective brushes to raise the same. Each of these fingers 48 is held in its normal position by a spiral spring 49, and is adapted, when the rod 25 is twisted and

the corresponding pin moves into a groove 65 68 formed in each, to yield and be forced out of vertical alignment with the fingers upon the other carriers. By this construction it is possible to select any predetermined brush by raising the brush rod 25 until the corresponding pin 47 is adjacent the groove 68 in the corresponding finger when it is given a twist which causes the said pin to engage the groove of the respective carrier and be locked therewith. By examining the relation of the other pins to the grooves of their respective fingers at this moment of twisting it will be evident that due to the method of spacing the fingers from the pins, none of the others are in alignment. That is the 70 pins below the selected brush are above the grooves of their respective fingers while the pins above said brush are below the grooves of their respective fingers. As is shown in Fig. 5, the yielding mounting of the fingers 75 has permitted the selected brush to be swung to the right by its pin 47 so that the upward movement of the rod 25 may be continued until the selected brush reaches the desired terminal, the pins above the brush selected, 80 which have not yet passed their respective fingers in the upward movement, passing to the right of their fingers, as illustrated in Fig. 6. When the required terminal has been reached the upward movement of the 85 rod is arrested and it is held elevated pending conversation, by the pawl 39 engaging the rack 44 formed on the rod 25, after which said pawl is disengaged therefrom and the rod and brush restored by any suitable 90 means, preferably gravity. The upward movement of this rod may be caused by contact either with the low-speed pulley 52, which is rigidly secured to a constantly rotating shaft 50 or with the high-speed pulley 105 51 rigidly secured to a constantly rotating shaft 53, or with both intermittently. These shafts may rotate at a relative speed of one to ten. The contact of the rod with these pulleys may be controlled by any suitable 110 apparatus, that shown being electromagnets 23 and 24 which when energized, act through the levers 54, 55, and idler pulleys 78, 79 respectively, to cause the brush rod 25 to engage with either pulley and slowly or rapidly 115 elevate the brush rod. The initial movement of said rod may be caused by the energization of the low-speed clutch magnet 23. At the instant one of the pins on the brush rod 25 is adjacent the groove in the finger of 120 the brush serving the desired hundreds, current is applied to shift magnet 45 which acts through the shift arm 42 to give said brush rod a twist causing the corresponding pin 47 to engage with the groove 68 in the finger 125 48 of the desired brush and seize the same. The brush rod 25 in continuing its movement is elevated to the end of the brush selecting

range, when the rack 44 engages with the retaining pawl 39. Current is then either maintained applied to the magnet 23 of the low-speed clutch 76 to continue the elevation of the brush rod 25 and selected brush at low-speed to the desired terminal, or transferred to the magnet 24 of the high speed clutch 75 which elevates the brush rod and brush at a relatively higher speed 10 over the tens terminals, when current to the magnet 24 is cut off and again supplied to the magnet 23 shifting the rod 25 from the high speed to the low speed clutch. It is then raised again at low speed until the desired units terminal is reached by the brush, where it is held by the pawl 39.

When it is desired to restore the mechanism, an impulse of current applied to magnet 46 will cause the shift arm 42 to twist 20 the rack 44 off the pawl 39. This twisting movement also disengages the pin 47 from the groove 68 in the finger 48 of the selected brush and the rod and brush fall back to normal. If, however, the brush should stick, 25 the brush rod 25 being relatively heavy will through the engagement of the pin 47 with the lower guide 72, force the brush carrier 28 to normal, its downward movement, as well as that of the pin 47, being stopped by 30 the screw 77 in the floor 67 of the corresponding section. The supply of current to these clutch controlling magnets may be governed by means of a commutator 57 shown in Figs. 2, 7 and 9, the contact arm 58 and 35 metallic segments 59 sending back impulses to a sender or other suitable mechanism by means of which the preliminary movement of the brush rod 25 during brush selection may be controlled, the contact brush 60 and metallic 40 segments 61 sending back impulses by means of which the upward movement of the selected brush over the tens line terminals may be controlled, and the brush 58 serving also with the metallic segments 62 45 to send back impulses by means of which the travel of the brush over the units terminals may be controlled. The brush 63 and the continuous metallic segment 64 supplies return or ground to these circuits. The brush 50 rod 25 is swiveled at 65 in order to allow the upper portion of it to freely twist without interference by the clutch mechanism.

As shown most clearly in Figs. 2 and 13 arms 69 overlie projections 70 of the carriers 55 and thus prevent the brushes being accidentally elevated by the brush rod 25. The twisting of this rod and consequent engagement of a pin with the corresponding finger of the selected brush however causes the projection 60 70 of the finger to slide from under its retaining arm 69.

The magnets 45 and 46 are each built of steel in order that the residual magnetism may hold the shift arm 42 and thereby the

brush rod 25 in either position, thus avoiding the use of springs.

I claim:

1. In a selector, the combination with a row of terminals divided into sections, a brush for each section having a finger by which it may be moved, an actuating rod for said brushes having a pin for each brush, the distance from the normal position of each pin to its corresponding finger varying in arithmetical progression with the successive 75 brushes, means for actuating said rod, and means for twisting said rod to cause one of its pins to pick up the corresponding brush during its travel.

2. In a selector, the combination with a 80 row of terminals divided into sections, a brush for each section having a finger by which it may be moved, a brush rod having a pin for each brush, the distance from the normal position of each pin to its corresponding finger varying in arithmetical progression with the successive brushes, means for elevating said rod at low speed, means for twisting the rod during said movement to seize one of said brushes, and means for 85 thereafter raising the said brush at another rate of speed to the desired terminal.

3. In a selector, the combination with a vertical row of terminals divided into sections, a brush for each section having a finger, a brush rod having a loose connection with each brush, pins carried by said rod each adapted to engage and lift a particular brush, the distance from the normal position of each pin to the corresponding finger increasing in arithmetical progression with the different brushes, means for elevating said brush rod, a magnet adapted when a pin upon said rod is adjacent the finger of the desired brush to angularly displace the rod 100 105 to cause said pin to seize said brush, means for arresting the said brush at the desired terminal, and means for thereafter releasing the same.

4. In a selector, the combination with rows 110 of terminals, brushes therefor, a constantly rotating pulley, an elevating member for the brushes, an idler pulley, and means for causing said idler pulley to force said elevating member into engagement with said constantly rotating pulley.

5. In a selector, the combination with a row of terminals divided into sections, a brush for each section, a continuously rotating pulley, a rod adapted to elevate said 120 brushes singly, an idler pulley engaging said rod, and an electromagnet adapted to cause said idler pulley to force said rod into engagement with said pulley.

6. In a selector, the combination with rows 125 of terminals, brushes therefor, continuously rotating pulleys, a rod adapted to elevate said brushes passing between said pulleys

- and being normally out of engagement with either, idler pulleys adapted to engage said rod and means for causing either of said pulleys to force said rod into engagement 5 with the corresponding constantly rotating pulley.
7. In a selector, the combination with rows of terminals, brushes therefor, a pair of pulleys each constantly rotating at a different speed, an elevating rod for said brushes passing between said pulleys and out of engagement with either, a pair of electromagnets, levers controlled thereby, an idler pulley for said rod carried by each lever, one of said 10 idler pulleys upon the energization of its magnet forcing said rod into engagement with the corresponding power pulley.
8. In a selector, the combination with rows of terminals, brushes therefor, a constantly rotating member, an elevating member for the brushes, an idler member, and means for causing said idler member to force said elevating member into engagement with said constantly rotating member.
- 25 9. In a telephone switch, a support, a plurality of independently movable brushes thereon, means for moving said support longitudinally, and means for selectively rotating said support during its longitudinal movement to render active a predetermined brush.
10. In a telephone switch, a longitudinally movable support, a plurality of independently movable brushes thereon, electro- 30 magnetic means for selectively rotating said support during its longitudinal movement to select and render active a predetermined brush, and means for determining the time of such rotation.
- 35 40 11. In a switch, a row of stationary terminals divided into sections, a longitudinally movable support, a normally inactive brush individual to each section respectively, operatively associated with said support, and means for rotating said support during its longitudinal movement to render active any desired brush.
12. In a switch, a row of terminal sets divided into sections and a corresponding plurality of normally inactive brush sets, a 45 rotatable and longitudinally movable brush selecting device, and electromagnetically controlled means for selectively rotating said device during its longitudinal movement to render active any one of said brush sets.
- 50 13. In a switch, a longitudinally movable rod, a plurality of brush carriers normally loosely mounted thereon, coöperating locking members on said rod and brush carriers respectively, and means for rotating said 55 rod during its longitudinal movement to cause operative engagement of the locking members individual to a desired brush carrier to temporarily secure said brush carrier to said rod.
14. In a switch, a longitudinally movable support, a plurality of brush sets normally loosely mounted thereon, locking means individual to each set for temporarily securing the brushes thereof to said support, and 60 means for rotating said support during its longitudinal movement to effect the operation of the locking means of any desired set.
- In witness whereof, I hereunto subscribe my name this 7th day of July, A. D. 1911. 75

JOHN NEWBERRY REYNOLDS.
